UNITED STATES PATENT OFFICE

WILLIAM E. ELLING, OF LONG ISLAND CITY, NEW YORK

FOLDABLE OR COLLAPSIBLE BOAT

Application filed January 14, 1931. Serial No. 508,654.

This invention relates to improvements in foldable or collapsible and portable boats for pleasure cruises and other useful purposes which are conveniently to be transported in 5 their folded condition, and it is the principal object of my invention to provide a boat of simple and therefore inexpensive construction yet durable and efficient in operation, which is water-tight when unfolded and 10 capable of carrying an adequate load, yet light and portable.

Another object of my invention is the provision of hinge constructions for the connection of the parts of a watertight folding structure allowing a ready folding and producing a water-tight closure.

Still another object of my invention is the provision of a collapsible boat, the walls of 20 which are made of thin material, (just thick enough to be watertight), and stiffened by longitudinal laths or battens on the outside and cross-laths on the inside of the boat.

A further object of my invention is the provision of a foldable or collapsible portable 25 boat having a flat bottom with straight or curved side edges equipped at its ends with a hingedly connected, rigid end element allowing a ready folding of the boat, or allowing the insertion of a stationary end piece to 30 provide a boat for use with outboard motor which is secured by means of suitable clamps.

A still further object of my invention is the provision of a foldable or collapsible boat which may either be made of wood or metal 35 and the parts of which are connected by water-tight hinges or other suitable means.

Other objects of my invention are foldable or collapsible boats having a straight 40 keel at centre line and a curved form of edges at connection of sides and bottom, thus, creating U shaped end sections of boat and a W shaped midship section. The end pieces being hingedly connected to each other and 45 to the side walls.

These and other objects and advantages of my invention will become more fully known as the construction thereof proceeds, and will then be specifically defined in the ap- 50 pended claims.

In the accompanying drawings forming a material part of this disclosure:

Fig. 1 is a perspective view of a folding or collapsible boat constructed according to my 55 invention.

Fig. 2 is a side elevation of the boat collapsed.

Fig. 3 is a central section through the boat, 60 Figure 1.

Fig. 4 is a similar section through the boat, 65 Figure 2.

Fig. 5 is a fragmentary top plan view of the boat folded.

Fig. 6 is an enlarged side elevation of a hinge mechanism to be used with my folding 65 boat.

Fig. 7 is a perspective view of a modified form of my folding or collapsible boat.

Fig. 8 is a side elevation of the same folded.

Fig. 9 is a cross-section through the boat, 70 Figure 7.

Fig. 10 illustrates another modified form of my folding boat, looking at bottom.

Fig. 11 shows the boat, Figure 10, folded.

Fig. 12 illustrates the construction of boat 75 walls, when made of wood or similar material.

Fig. 13 is a section on line 13—13 of Figure 12, and showing the fore and aft alternate location of stiffening batten so these are not in 80 way of each other when folded.

Fig. 14 is a sectional side elevation of a hinge.

Fig. 15 is a sectional view of another form 85 of hinge so-called double piano hinge.

Fig. 16 is a fragmentary side elevation of a watertight connection of said and bottom without hinge.

Fig. 17 is a view similar to Figure 16 of another form of hinge.

As illustrated in Figures 1 to 5, the preferred form of my collapsible boat consists of two side parts 10, 11, and a bottom made in two parts 12, 13, hinged together along the 95 keel 14, by means of hinges 15, 15', while the side parts are hingedly connected to the bottom parts by means of the hinges 16, 16' of any desired type for instance such as described hereafter.

The boat thwarts are designated 17 and 18 100

respectively and are removably held between the side parts 10, 11, and supported against the bottom by means of braces 19 and 20 respectively.

5 The end pieces consist each of two parts 21, 22, and 21', 22' respectively hingedly connected to each other along their median lines 23, 24, respectively, and to the side walls by means of suitable hinges 25 for instance such as to be more fully described hereafter.

10 The end pieces are connected at their lower ends to the bottom parts in any well known manner watertight yet allowing a ready separation of same for folding. This construction will make the boat more seaworthy than the U-shaped boats, as the side walls are inclining outwardly as for instance shown in Figure 3.

15 In Figure 6, I have illustrated a hinge construction which I may use to connect the bottom and side parts of the boat.

20 The hinge construction may be used either as single hinge as shown on the left hand side or as double hinge as shown on the right hand side of Figure 6.

25 Each of these hinges consists of three parts, part 26, shown as metal side of a boat with stiffening batten 27 on inside and having a curved end part 28. Part 29 having a straight element bolted, as at 30, to part 26, and having its lower end formed into a hinge element 31 in form of a curved finger into the curve of which engages a curved finger 32 of the third part 33 also with stiffening batten 34 on inside. In order to make the hinge connection water-tight a piece of felt 34 is entered and held by hooked end 36.

30 In the double hinge shown at the right hand side of the Figure 6 the bottom halves 34'', 34' have inner curved fingers 35, 35' adapted to be engaged by the curved and hooked ends 36, 36' spaced from the ends of fingers 35, 35' and pieces of felt 37, 37' are interposed between the individual finger ends 35 and held by hooked ends 36, 36'.

35 A straight part 38 formed with the inner ends of fingers 36, 36' is bolted as at 39 to the straight part 40 of rounded or curved fingers 41, 41' engaging the backs of elements 34, 34'.

40 In Figures 7, 8, and 9, I have illustrated a modified form of my invention according to which the boat has a bi-partite rounded flat bottom the parts of which are designated 42, 42' and hingedly connected as at 43, and the outwardly curved side walls 44, 45, are hingedly connected to the bottom parts, as at 46, 47, respectively.

45 As shown the sides of the boat are kept apart in the unfolded position of the boat by a thwart 48 braced against the bottom by a removable brace 49. In this form of my invention it is possible to close one of the ends by means of an end piece which may be secured to the boat's side walls and bottom by

suitable readily removable clamps in order to obtain in this manner an outboard runner and speed boat, or both ends may also be closed in such manner.

50 In the form of folding or collapsible boat 70 illustrated in Figures 10 and 11, the boat has a flat bottom 50, 52 with straight or curved side edges, to which the sides 51 are hingedly connected as at 53, 54, respectively. The bottom is at ends hinged upwardly as 75 indicated at 55, 56, by hinges 57, 58 when the boat is set up as such, and the ends of the side walls are hinged to the middle part thereof, as at 57, 58. The foregoing described boat shows the advantage of having 80 increased displacement at the ends.

85 It will be clear that the bottom parts can be connected to the side parts of the boat instead of by hinges by clamping the edges of the parts between two strips secured to the side or bottom parts and presenting a watertight closure.

90 It will also be evident that the lower edges of the side parts and the outer edges of the bottom parts must have absolutely homogeneously rounded forms in order to enable a perfect folding of the boat if the parts are for instance connected by hinges.

95 During the unfolding of the boat the bottom and the sides will bend proportionally until they assume an angle of 90° and the bend thus will correspond exactly to the bend of the margin which may be radial, which, however, in order to obtain a more ship-like form may have its main bend more towards 100 the ends.

105 The hinge hangers at the ends of the boat will compensate for the tension opposing the unfolding of boat and are preferably to be used in all forms of boats having curved side walls.

110 In Figures 12 and 13, I have illustrated the preferred form of wall construction for wooden boats in which the veneer pieces 59, 60, are laid against an intermediary muslin or canvas piece 61 or the like by means of which the veneer pieces are held together by stitching. This construction provides light, yet utmost strong boat walls. As illustrated, the preferred form of wall construction 115 in which a plate of any watertight material is stiffened by longitudinal laths or battens on the outside and cross-laths on the inside. It will be clear that this construction will take the necessary bend very easy.

120 Figures 14, 15, and 17, illustrate the preferred form of hinge constructions which I use in the formation of the various forms of my folding or collapsible boat.

125 As shown in Figure 14, the hinge is composed of a tube 62 open for about $\frac{1}{3}$ of its circumference and is adapted to receive a suitably smaller tube 63, the elongated shank or flanges of the hinge plates 64, 65, adapted to be secured to the walls 60, 67, to be con- 130

nected by the hinge. It will be evident that the flange of the smaller tube can be rotated for an angle of 90° to the other larger tube.

In Figure 15, I have illustrated a hinge which may be called a double hinge preferably to be used to connect the bottom halves 68, 69, of a boat to the keel 70. The hinge leaves 71 are attached by means of screws 72 to the keel. Brass strips 73 are fastened to bottom halves 68, 69, and press felt strips into the grooves of keel 70 to produce a water-tight closure.

As shown in Figure 16, water-tightness is obtained without any hinge by clamping or wedging, when unfolded, bottom 74 and felt strip 83 between strips 81, 82, attached to side 75.

The hinge hangers or link connections illustrated in Fig. 16 and Fig. 17 are located at the ends of the boat to compensate for the tension opposing the bend of bottom 74 and side 75 and include a pair of links 76, 77, pivotally connected as at 78 at their inner meeting ends, while the outer ends of these links are pivotally secured, as at 79, 80, to the sides and bottom respectively.

The hinge illustrated in Figure 17 connects the sides 84 of a boat with the bottom 85 which are connected by links 86, 87, pivotally connected at their meeting ends, and pivotally connected at their outer ends, as at 88, to a fitting on the side 84 and at 89 to a fitting at the bottom, while an ordinary hinge 90 connects both, and a felt layer 91 ensures a water-tight closure.

The operation and use of my foldable and collapsible boats will be entirely clear from the above description by simultaneous inspection of the drawings, and it will be understood that I have disclosed the preferred forms of my invention only as examples of the many possible ways to practically construct the same and that I may make such changes in the general arrangement of my device and in the construction of the minor details thereof as come within the scope of the appended claims, without departure from the spirit of my invention, so for instance I may provide cushioning material for the inside of the boats as well as the outside thereof made for instance of kapoc which serves as a protecting means for the boat and tends to make the same non-sinkable.

Having thus described my invention, what I claim as new and desire to secure by Letters Patent is:

1. A hinge construction for the parts of foldable boats comprising a large tube having a circumferential opening formed therewith, a smaller tube received in said larger tube, and hinge plates formed with said tube adapted to be secured to the walls to be connected by the hinge.

2. A double hinge for connecting the bottom halves of a foldable boat to its keel hav-

ing a groove, comprising hinge leaves, adapted to be attached to the keel, brass strips fastened to the bottom halves and felt strips in the grooves of the keel adapted to be pressed thereinto by said brass strips to produce a water-tight closure.

3. In foldable boats, a means for producing a watertight closure between the side walls and bottom of a foldable boat comprising strips attached to the side walls and a felt body between bottom and one of the side wall strips, and a means for spacing bottom and side parts apart allowing a folding of same against each other.

4. In a foldable boat a means for connecting the sides of the boat with its bottom, links allowing a folding, connecting sides and bottom, pivotally connected at their inner meeting ends and pivotally connected at their outer end to said sides and bottom, an ordinary hinge connection between side walls and bottom, and a felt layer for ensuring a water tight closure.

5. A collapsible, portable boat comprising a keel straight at its center line, two rigid yet outwardly warping bottom plates with straight center- and curved outer edges, rigid side walls, bendable in fore and aft direction with their lower edges formed to conform to the outer edges of bottom-halves, continuous metal hinge connections between said side walls and bottom plates and between keel and bottom plates, a curved connection at the side walls and a straight connection at the keel, said bottom and sides forming a rectangular section at the end of bottom and keel and an opening limit of the hinges between sides and bottom of 90° , creating a true W-shaped midship-section when unfolded, two rigid plates at each end of the boat hingedly connected to one another and to the side walls.

6. In a collapsible, portable boat of the class described, the combination of a straight connection of the bottom halves to the keel at the center line of the boat, and a curved hinge connection between the bottom halves and the sides of the boat, with an action limit of 90° of the hinges between bottom halves and sides, forcing the last named parts to form a true W at mid-ship section for keeping said parts horizontal and vertical respectively at the ends of the boat, two end plates hingedly connected to each other and to the sides of the boat.

7. In a collapsible, portable boat of the class described, two rigid plates at each end of the boat hingedly connected to each other and to the side walls, forcing said end plates to press automatically against the end edges of the bottom of the boat when same is opened or unfolded by spreading the side walls outwardly by a thwart or seat.

8. A hinge construction for collapsible boats comprising the side of a boat having

a curved lower end, a straight element bolted to said side of the boat, a hinge element formed at the lower end of said element including a curved finger, the bottom of the boat having a curved outer edge constituting a second hinge element adapted to press into a piece of felt entered between and held by the finger of the first named hinge element.

Signed at New York, in the county of New York, and State of New York, this 9th day of January, A. D. 1931.
